UNITED STATES PATENT OFFICE.

CHARLES WILLIAM BEISER, OF BROOKLYN, NEW YORK, ASSIGNOR TO
AMERICAN SOLDIER COMPANY, OF BROOKLYN, NEW YORK, A COR-
PORATION OF NEW YORK.

DEVICE FOR PACKING AND SUPPORTING TOYS.

No. 834,452.

Specification of Letters Patent.

Patented Oct. 30, 1906.

Application filed May 11, 1905. Serial No. 260,007.

To all whom it may concern:

Be it known that I, CHARLES WILLIAM BEISER, a citizen of the United States, residing at Brooklyn, Kings county, New York, have 5 invented certain new and useful Improvements in Devices for Packing and Supporting Toys; and I do hereby declare the following to be a full, clear, and exact description of the invention, such as will enable others 10 skilled in the art to which it appertains to make and use the same.

This invention relates to certain improvements in devices for packing and supporting toys and the like, and relates more particularly to improvements on the constructions shown in my patent for devices for packing and supporting toys, No. 782,817, dated February 21, 1905.

An object of the invention is to provide 20 certain improvements in constructions and arrangements of parts whereby highly-efficient and advantageous means will be produced for supporting toy figures or the like in either the "display" or "flat" position on the tray, supporting-card, or the like, and permitting the quick and easy shifting of such toys from one to the other of said positions, and permitting easy removal of said toys from or of application thereof to said 30 means.

The invention consists in certain novel features in construction and arrangements or combinations of parts, as more fully and particularly explained hereinafter.

Referring to the accompanying drawings, which show a preferred embodiment of my invention, Figure 1 is a perspective view of a packing case or box, partially broken away to show a toy supporting or carrying tray or 40 sheet in the box and having several toys thereon arranged in the horizontal or flat position. Fig. 2 is a detail sectional view taken through the tray, toy-base, and the attaching means between the toy and tray, a portion of the toy figure being broken away. Fig. 3 is a detail perspective view of a toy and its attaching and supporting means, the toy and means being shown separated and the tray shown broken away. Fig. 4 is a top 45 plan of a portion of the tray, showing the

base portion of a toy-figure and the attaching means between the toy and base, the toy figure being broken away.

In the drawings, 2 is any suitable packing-box adapted to movably receive a tray, sheet, or the like carrying the toys. These boxes are usually although not necessarily, made of cardboard or the like of the slip-cover type, although the trays can be packed in any suitable boxes.

3 is the tray or sheet to which the toys are attached, although the toys can be attached to any suitable support. I usually employ stiff sheets or flat trays of cardboard or other equivalent material of a size to fit in boxes prepared therefor, so that the tray can be removed from the box and placed thereon for display or can be displayed while in the box when the cover is removed.

4 designates the toy figures, each of any 70 suitable form or configuration, although each is usually cast of suitable metal with a flat rectangular base 5, which will form a firm bearing or base for the toy in holding the same in the natural upright position when 75 removed from the attached devices. Each base is usually approximately oblong in form—that is, with the parallel straight transverse end edges and the straight longitudinal rear edge, and, if desired, with the 80 straight longitudinal front edge parallel with said rear edge.

A separate fastening, attaching, or supporting device is provided for such toy for detachably receiving the toy and for hinging 85 or pivotally joining the same to the tray. For this purpose I show a base-plate 6 for each toy, having a hinged or flexible connection with the tray.

Each plate 6 consists of a usually approximately rectangular or oblong piece of sheet metal or other suitable material, having its opposite ends formed with parallel transverse slideways or grooves 6, formed by bending the end of the plate upwardly and over 95 the top surface of the plate, so that the ends of the plate are approximately hook-shaped or U-shaped in cross-section. The rear longitudinal edge of the plate is usually bent up and curled over to form the longi- 100

tudinal attaching-eye 6", forming a stop at the rear edge of the plate and approximately between the rear ends of said slideways 6'.

7 is the attaching or hinge member between the tray and base-plate and consists of a U-shaped wire or staple, the straight transverse portion of which passes through the eye 6" and forms the hinge-pivot on which the base-plate swings. The legs of the staple are passed through the tray and clenched at the under surface of the tray or otherwise bent down or fastened in or to the tray to properly secure the staple thereto and enable the transverse portion thereof to perform its functions as the hinge-pivot and the entire staple to perform its function of properly attaching the base-plate.

The base-plate is so formed that the toy-base can slide thereonto from the front edge 20 of the plate with the ends caught and sliding under the overturned ends of the plate which properly hold the toy-base down on the base by frictional engagement with the base ends. The toy-base rests on the flat upper face of 25 the base-plate, which is usually of about the same dimensions as such toy-base. The eye at the rear edge of the base-plate forms a stop for the rear edge of the toy-base, while the front edge of the base-plate is open so 30 that the toy can slide thereinto and therefrom, and hence permit easy and ready assembling of the parts at the factory, and also constitute a source of amusement for children in playing with the toys.

35 When the toys are in the upright or display position, the base-plates form firm supports for upholding the figures in the standing or display positions.

When the toys swing between the vertical 40 and horizontal positions, the comparatively long straight eyes 6" rest and rock on the top surface of the tray and form a comparatively elongated bearing, and when the toys are in the horizontal position, resting on the tray, 45 said eyes also rest on the surface of the tray and form a bearing which aids in holding the toys against lateral play and in their proper positions.

Each tray usually carries a multiplicity of 50 the independent and separately mounted toys, which can be simultaneously rocked to either the horizontal or upright positions by tilting or reversing the tray and then returning the tray to its normal position.

55 When the toys are in the horizontal position, the tray carrying the same can be packed in a shallow comparatively cheap box, and yet the toys can be all quickly brought to display position when the box-cover is re-

moved or when the tray is removed from the 65 box.

What I claim is—

1. A carrier; in combination with a toy having a flat base with approximately parallel end edges, a flat swinging base-plate having approximately parallel transverse end slideways adapted to slidably receive the ends of said toy-base, said base-plate being open at the front edge so that the base can slide into and from said slideways from the 70 front, and a hinge connection between the carrier and base-plate.

2. A tray, in combination with a toy having a flat approximately oblong base, a base-plate approximately oblong in shape to receive said toy-base and having its ends bent back over its top face to form slideways open at the front ends to slidably receive and overlap the ends of said base, and a hinge connection at the rear edge of said base-plate 80 and confining the same to the tray.

3. A tray, in combination with several separate toys adapted to stand in upright position on the tray or to lie in the horizontal position thereon, each toy having a flat base 85 with projecting ends, base-plates for said toys, each base-plate having transverse slideways open at the front ends and adapted to receive the ends of the bases and lap over the same to hold the bases down on the plates 90 and permit the same to slide from the front edges of the plates to and from the same, each plate having a pivot-eye at the rear edge thereof and forming a stop, and a hinge and fastening connection between each eye 95 and the tray.

4. A tray, in combination with a toy adapted to stand in upright position on the tray or to lie in the horizontal position thereon and having a flat base with projecting ends, a 100 base-plate for said toy having a transverse slideway open at the front and adapted to slidably receive the ends of said base and lap over the same to hold the base down on the plate and permit the same to slide to and from said plate, said plate having a pivot-eye at the rear edge thereof, and a fastening-staple having its horizontal portion passed through said eye and forming a hinge-pivot on which said plate and toy swing and having 110 its legs passed into and secured in said tray, substantially as described.

In testimony whereof I affix my signature in presence of two witnesses.

CHARLES WILLIAM BEISER.
